UNITED STATES PATENT OFFICE.

DAVID EARL DE LAPE, OF BOSTON, MASSACHUSETTS.

RETTING TANK.

Application filed November 1, 1924. Serial No. 747,248.

This invention relates to retting tanks and has for its object the provision of a device for retting fibrous plants, either by treating the plants with heated liquors or by a prolonged maceration in cool or cold liquors with the bacteria process, the device being capable of not only retting fibrous plants but for dyeing loose fibers or cloth in small sections or bolts or for drying the fibers and cloths.

A further object of the invention is the provision of a device which may not only be used for retting, degumming or scouring fibers according to whether the fibers are vegetable, animal or artificial but may be used in the preparation of all kinds of pulps and for the manufacture of absorbent cotton or absorbent materials from China grass, or ramie, or the same may be employed in all forms of cooking, rinsing, and draining all forms of material or for softening, or animalizing, or water-proofing various fibrous cloths and felts as well as for starching; or the device may be used in all processes on fibers and fabrics where the circulation of liquors are essential and where steam is employed to agitate the hot liquors or compressed air is used for agitating cold liquors.

A further object of the invention is the provision of a device in which fibers are adapted to be treated and in which liquors are circulated, the liquors being boiled and agitated at the surface whereby the fibers are not unduly macerated and thus destroyed.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a view in perspective of a retting tank constructed in accordance with the principles of my invention.

Figure 2 is a vertical transverse section of the device.

Figure 3 is a vertical transverse section at one end of the retting tank.

Figure 4 is a longitudinal section taken along the line 4—4 of Figure 3.

Referring more particularly to the drawings, 1 designates a concrete floor of a building which has an elevation as shown at 2 and sloping sides 3 and gutters 4 so that the water drained from the retting tank will flow in opposite directions and follow the gutters 4 which are in communication with the usual sewerage pipes of the municipality or the gutters 4 may direct the liquors from the tanks to other tanks where they are recovered when desired and for the sake of economy.

The floor 5 of the double tank is elevated above the slope of the sides 3 by blocks 6. Secured to the floor and adjacent the longitudinal edges of the floor are side walls 7 and 8. Running centrally of the tank is a partition 9 which separates the tank into two compartments.

The tank or compartments are closed at their ends by walls 12 and 13. Cleats 14 are disposed longitudinally of each compartment and on the floor of said compartment and adapted to support a screen 15.

The ends of each compartment are provided with metallic partition plates 16 which have a flanged portion 17 bent at right angles to the plate and secured to the side walls of the tank. The lower ends of the plate 16 rest upon the cleats 14. The plates 16 are cut off at an angle and are higher at their inner ends adjacent the partition 9 than at their outer ends where connected to the side walls.

A sheet metal lining or partition 18 extends longitudinally of each chamber of the tank and spaced from the opposite faces of the partition 9. The lower end of the lining is bent at right angles as shown at 19 and secured to the bottom of the floor by a cleat 14. The lining is secured to the inner ends of the plate 16 and has a projecting portion 20 adjacent its top and bent inwardly to form the closure for the ends of the heating chambers 21 adjacent the partition 9. As shown in Figures 2 and 3, the end members 20 terminate at a point adjacent the steam pipe 22 of the heating chambers. The upper edges of the metal linings 18 terminate at the same level with the inner upper ends of the metal plates 16.

Located above the heating chambers 21

are a pair of oppositely disposed baffles 23 for causing the hot water which is boiling in the chamber 21 to be moved in opposite directions away from the partition 9 and 5 over the liquor and materials in the chambers 10 and 11. The steam pipes 22 may be of any approved form and have a vertical inlet pipe 24 controlled by a valve 25 for admitting steam to the pipe which passes out 10 through the outlet pipe 26 at one end of the tank.

The opening in the end member 13 where the outlet pipe 26 passes is provided with a gland or some form of sealing member 27 15 to prevent the loss of fluid at this point. The bottom 5 of the chambers adjacent the end and in the cells 28 and 29 which are located between the partition plate 16 and the end walls 12 and 13, respectively, are provided with openings 30 closed by a plug 31 which has a long handle 32 so that the same may be operated above the elevation of the liquors which is shown at 33.

Water is admitted to the tanks 10 and 11 25 by means of a pipe 34 having a universal connection at 35 whereby the same may be oscillated for supplying either tank with water. A valve 36 controls the flow of water through the pipe 34. A cold water pipe 37 30 is connected with a common pipe 39 and a hot water pipe 40 is also connected with the pipe, with pipe 40 being controlled by valve 41 and pipe 37 by valve 42 so that either cold or hot water may be admitted to 35 either of the tanks when desired.

Headed lugs or nails 43 are provided at the upper edge of the partition 9 for the purpose of receiving the rings 44 secured to 40 an edge of a wire fabric 45 which is adapted to be placed within the tank and held at its opposite edge by nails or lugs 46 secured in the top of the side walls 6 and 7 of the tank. At points between the rings 44 strands of wire fabric 45 are secured over other nails 43.

A truck 47 is adapted to be run along the side of either of the tanks 10 and 11 and is adapted to receive the material 48 which has been retted or cooked or otherwise treated in the compartments 10 and 11.

The operation of my device is as follows:

Liquors are shown in the tank at a certain level and the steam is turned on so that when it passes through the pipes 22 water in the compartments 21 will be boiled and the agitated liquors in the tanks will be forced upwardly and beneath the baffles 23 and out over the surface of the material which is treated. The water as it cools passes towards the bottom of the tank through the materials being treated and the screen 15 after the materials have been placed in either of the tanks or in both tanks by means of the wire fabrics 45. The fibrous materials will float and be normally maintained in position between the top and bottom surfaces

of the liquors. When it is desired to remove the material from the tanks it is only necessary to remove the inner edges of the wire fabric 45 and elevate the same, as shown in Figure 2, towards the outer walls with the wire fabric being held by the nails at the upper edges of the side walls. When the screen or wire fabric is raised sufficiently the materials which have been treated will be dropped into the truck 47. When it is desired to discharge the liquors the handles 32 are raised and cause the liquors to run through the discharge openings 30 in the bottom of the tanks.

The construction of the valves or stoppers 31 and the handles 32 is such that the handles, being formed of some material which does not readily absorb heat and projecting above the top of the tank, permits the workmen to remove the rubber stopper 31 which is rigidly connected with the handle 32, without any danger of scalding or burns from a heated handle.

It will be seen that by my process the kind and quality of liquors employed depends 90 upon the kind of materials treated in the tanks. When the liquors are heated by the steam coils in the heat chamber the liquor boils over and is projected upon the top of the liquors in the main portion of the tank 95 and upon the material where the liquors still continue to boil. The boiling of the liquors is maintained because of the constant circulation of the liquors since the cooler liquors settle to the bottom of the tank and pass out beneath the lower edges of the partition 16 and into the chambers 28 and 29 whence they find a way back to the bottom of the heating chamber and are again heated and caused to 100 boil and again projected by the baffle upon the level of the liquors in the main retting tank.

The pairs of independent tanks which are formed by dividing a large tank with an intermediate wall are placed in batteries 110 along the floor of the building and with the steam pipes connected for continuous operation of all the tanks, the arrangement being such that 8 hour shifts of workmen are required to operate continuously the series of tanks so that certain of the tanks are being 115 discharged while others are being filled and while still others are in various processes of operation.

It will be seen that by my improved tank 120 any kind of materials may be treated and in any manner desired where a circulation of the waters or liquors are required, and that such fabrics or materials may be readily placed in the tanks or may be just as readily 125 removed by raising one end of the wire netting 45 for dumping the materials directly into a truck. The materials, especially vegetable fibers, which are to be retted in the tanks, are maintained in longitudinal aline- 130

ment since the boiling of the liquors occurs at the surface and does not disturb the fibers. If the liquors were boiled and forced up through the fibers the same would be agitated and disturbed and their usefulness greatly destroyed or impaired by their agitation. My improved device prevents any disturbance of the fibers because of the fact that the ebullition of the liquors is maintained at a point which is never less than the height of the outer ends of the plates 16.

It must be borne in mind that an important feature of the invention is the fact that while the surface of the liquor in the tank receives the boiling liquor directed by the baffle 23 from the restricted heating spaces or chambers 21, the liquor in the tank is never in a state of agitation so that it would cause a disturbance in the fiber and therefore ruin the same. The boiling liquor directed by the baffles 23 travels in a horizontal plane towards the outer walls of the tank. The liquors descend by gravity through the fibers 48 and due to the variation between the temperature of the upper and lower surfaces of the liquor the fibers are maintained in a floating position between the upper and lower portions of the liquor and spaced from the top and bottom surfaces. The treatment of the fibers by this method and apparatus is such that the fibers will be maintained in substantially the position in which they were placed in the tank so that when they are removed they will not be in a tangled and worthless condition.

The apparatus and the process may be applied for bleaching and carbonizing of fibers or cloths or for cooking any and all materials whether in containers or in bulk and where it is necessary to do such cooking or boiling without disturbing or disarranging the substances. The device may be employed for sterilizing milk in containers whether taken singly or in the aggregate; for laundering or cleaning cloths or loose cotton, jute, hemp, silk, wool, flax or any and all materials that are commonly laundered, degummed or pulped; and also for sterilizing instruments, tools or other objects in small quantities or in bulk. The device also may be used for degumming cotton or other waste or linters and for stripping, that is removing dyes, from colored waste, rags or shoddy.

When the plugs or valves 31 are removed the liquors in chambers 28 and 29 will immediately discharge therefrom and will fall more rapidly in said chambers than in the tanks per se or in other words in the portions of the tanks defined by the end walls 16, partitions 18 and the side walls 7 or 8.

What I claim is:

1. A retting tank having a bottom, end and side walls, partitions spaced from the end walls, a partition spaced from one side wall and terminating short of the upper end

of said side wall, a baffle located above the last mentioned partition, and heating coils located between the last mentioned partition and the adjacent side wall for heating liquor in the tank for causing the same to boil over 76 and be discharged over the edge of said partition and into the main body of the tank, and means connecting said partition at the ends thereof to an adjacent side wall, said means terminating short of the bottom of 75 the tank for placing the heating chamber in communication with the tank.

2. A retting tank having a bottom, end and side walls, partitions spaced from the end walls, a partition spaced from one side 80 wall and terminating short of the upper end of said side wall, a baffle located above the last mentioned partition, heating coils located between the last mentioned partition and the adjacent side wall for heating liquor 85 in the tank for causing the same to boil over and be discharged over the edge of said partition and into the main body of the tank, and bars on the bottom of the tank adapted to maintain the first mentioned partitions 90 elevated above said bottom, and means connecting said partition at the ends thereof to an adjacent side wall, said means terminating short of the bottom of the tank for placing the heating chamber in communication 95 with the tank.

3. A retting tank having a bottom, end and side walls, partitions spaced from the end walls, a partition spaced from one side 100 wall and terminating short of the upper end of said side wall, a baffle located above the last mentioned partition, heating coils located between the last mentioned partition and the adjacent side wall for heating liquor 105 in the tank for causing the same to boil over and be discharged over the edge of said partition and into the main body of the tank, the first mentioned partition plates adjacent the ends of the tank having one of their ends secured to the side wall while the other end 110 is connected with the last mentioned partition.

4. A retting tank having a bottom, end and side walls, partitions spaced from the end walls, a partition spaced from one side 115 wall and terminating short of the upper end of said side wall, a baffle located above the last mentioned partition, heating coils located between the last mentioned partition and the adjacent side wall for heating liquor 120 in the tank for causing the same to boil over and be discharged over the edge of said partition and into the main body of the tank, the first mentioned partition plates adjacent the ends of the tank having one of their ends 125 secured to the side wall while the other end is connected with the last mentioned partition, the last mentioned partition being secured to the bottom of the tank.

5. A retting tank having a bottom, end

and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of the liquors in the tank whereby ebullition of the liquors is maintained at the surface of the liquors in the tank, and means connecting said partition at the ends thereof to an adjacent side wall, said means terminating short of the bottom of the tank for placing the heating chamber in communication with the tank.

6. A retting tank having a bottom, end and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of the liquors in the tank whereby ebullition of the liquors is maintained at the surface of the liquors in the tank, and a screen located above the bottom of the tank, and means connecting said partition at the ends thereof to an adjacent side wall, said means terminating short of the bottom of the tank for placing the heating chamber in communication with the tank.

7. A retting tank having a bottom, end and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of the liquors in the tank whereby ebullition of the liquors is maintained at the surface of the liquors in the tank, a screen located above the bottom of the tank, a flexible carrier adapted to be removably connected with the opposite side wall of the tank whereby when one side edge of the flexible member is elevated the materials in the tank will be raised and discharged from said tank.

8. A retting tank having a bottom, end and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of

the liquors in the tank whereby ebullition of the liquors is maintained at the surface of the liquors in the tank, and partitions spaced from the end walls and forming discharge chambers at the ends of the tank.

9. A retting tank having a bottom, end and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of the liquors in the tank whereby ebullition of the liquors is maintained at the surface of the liquors in the tank, partitions spaced from the end walls and forming discharge chambers at the ends of the tank, the top edges of said partitions being inclined at an angle to the horizontal so that foreign matter floating upon the liquors will be discharged across the lower ends of the partitions into the discharge chamber.

10. A retting tank having a bottom, end and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of the liquors in the tank whereby ebullition of the liquors is maintained at the surface of the liquors in the tank, partitions spaced from the end walls and forming discharge chambers at the ends of the tank, the top edges of said partitions being inclined at an angle to the horizontal so that foreign matter floating upon the liquors will be discharged across the lower ends of the partitions into the discharge chamber, the highest portion of the partition being located adjacent the heating chamber so that the foreign matter is discharged adjacent a side wall which is remote from the heating chamber.

11. A retting tank having a bottom, end and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of the liquors in the tank whereby ebullition of the liquors is maintained at the surface of the liquors in the tank, said heating chamber being located adjacent one side wall, and partitions connected with the outer wall of the heating chamber extending to

the opposite side wall of the tank and rigidly connected therewith, the top edges of the partitions decreasing in height from the heating chamber to the remotely located side walls.

12. A retting tank having a bottom, end and side walls, a heating chamber in said tank, said tank adapted to be partially filled with liquor with the heating chamber open at its bottom to the liquors in the tank, a heating means in the heating chamber for causing ebullition of the liquors in the heating chamber, and means connected with the heating chamber for causing the boiling liquors to be projected upon the surface of the liquors in the tank whereby ebullition of the liquors in the tank, said heating chamber being located adjacent one side wall, and partitions connected with the outer wall of the heating chamber extending to the opposite side wall of the tank and rigidly connected therewith, the top edges of the partitions decreasing in height from the heating chamber to the remotely located side walls, a screen located above the bottom of the tank and extending between the heating chamber and the remotely located side wall and the partitions at the ends of the tank.
13. A retting tank having a bottom, end and side walls, partitions spaced from the end walls to form discharge chambers, a partition spaced from one side wall and con-

nected with said wall to form an enclosing heating chamber with the end walls having an opening for placing the heating chamber in communication with the tank, a baffle located above the heating chamber for causing liquor which is heated in the chamber to be discharged upon the surface of the liquor in the tank, the bottom of the discharge chambers being provided with openings for discharging the spent liquors, and plugs for closing said openings provided with handles projecting above the top of the tanks.

14. A retting tank having a bottom, end and side walls, an intermediate wall for dividing the tank in two independent tanks, partitions connected with opposite sides of the intermediate wall to form heating chambers which are open at the top and at the bottom of the end walls, partitions spaced from the end walls of each independent tank and connected with the outer wall of each heating chamber and having its other end connected with the side walls of the tank to form discharge chambers at each end of the independent tank, means cooperatively connected for heating the liquors in each of the heating chambers, said partitions adjacent the ends of the tanks being spaced from the bottoms of said tanks, and screens spaced from the bottom of the tanks and in horizontal alinement with the lower edges of said partitions.

DAVID EARL DE LAPE.
